[57] CLAIM

The ornamental design for a combined contact lens cleaner and holder or the like, as shown and described.

DESCRIPTION

FIG. 1 is a top plan view of the combined contact lens cleaner and holder or the like showing our new design; FIG. 2 is a front elevational view thereof, the rear view being a mirror image;

FIG. 3 is a side elevational view thereof, the opposite side being a mirror image;

FIG. 4 is a cross-sectional view thereof taken along the line 4—4 in FIG. 2;

FIG. 5 is a perspective view of the combined contact lens cleaner and holder or the like showing our new design.

FIG. 1FIG. 2FIG. 3FIG. 4

FIG. 5
